UNITED STATES PATENT OFFICE.

HENRY L. GRASMUK, OF NEWARK, NEW JERSEY, ASSIGNOR TO GEORGE KREMENTZ, JULIUS A. LEBNECKER, JOHN N. TAYLOR, THOMAS H. KREMENTZ, AND FRANK KREMENTZ, OF NEWARK, NEW JERSEY, DOING BUSINESS UNDER NAME OF KREMENTZ & COMPANY.

DESIGN FOR A LORGNETTE-CASE.

SPECIFICATION forming part of Design No. 35,312, dated November 26, 1901.

Application filed November 2, 1901. Serial No. 80,961. Term of patent 7 years.

To all whom it may concern:

Be it known that I, HENRY L. GRASMUK, a citizen of the United States, residing in Newark, county of Essex, and State of New Jersey, have invented and produced a new and original Design for a Lorgnette-Case, of which the following is a specification, reference being had to the drawings accompanying and forming a part of the same.

Figure 1 is an elevation of the front of the lorgnette-case. Fig. 2 is an elevation of the back of the lorgnette-case. Fig. 3 is a transverse section taken on line 3 3 of Fig. 1. Fig. 4 is a transverse section taken on line 4 4 of Fig. 2. Fig. 5 is a transverse section on line 5 5 of Figs. 1 and 2.

The elliptical body A of the front of the case (shown in Fig. 1) is joined to the handle B, having incurved sides, and the head C is joined to the upper end of the body, slight indentations being formed at the junctures between the body, the handle, and the head. The head C has a general calyx formation, the upper part of the head being in the form of a trefoil. Conventional leaf elements F, having undulatory curves, are used as a border for the body, and the head and the con-

ventional leaf elements E, having similar curves, are used as a border for the handle. These leaf elements E are interlaced at the 35 lower end of the handle to form the two apertures D. It will be noted that the border elements E of the handle form the two lanceolate panels K and L.

The front of the case is ornamented at the 35 juncture of the body and head with a female head G with flowing hair, and the body of the case is also ornamented by a fleur-de-lis H, arranged between the border leaf elements F.

The back of the lorgnette-case (indicated in Fig. 2) has the same design as the front, which has already been described, except that the fleur-de-lis H is not used to ornament the body of the case, so that an open 45 central panel I is formed on the body having an irregular shape.

What is claimed as new is—

The design for a lorgnette-case as shown and described.

HENRY L. GRASMUK.
